UNITED STATES PATENT OFFICE.

ERNEST E. BROTT, OF BURLINGTON, KANSAS.

EAVES-TROUGH HANGER.

SPECIFICATION forming part of Letters Patent No. 718,085, dated January 13, 1903.

Application filed February 27, 1902. Serial No. 95,857. (No model.)

To all whom it may concern:

Be it known that I, ERNEST E. BROTT, a citizen of the United States, residing at Burlington, in the county of Coffey and State of Kansas, have invented a new and useful Eaves-Trough Hanger, of which the following is a specification.

The present invention relates to eaves-trough hangers, and particularly those which are constructed of wire.

The aim of this invention is to provide an article of manufacture of this character made from a single wire having a rigid cross-bar and provided with peculiarly-constructed stops which engage the trough to prevent its collapsing, said article being capable of being manufactured at substantially the same cost as those known in the prior art.

The preferred manner of constructing the hanger is shown in the accompanying drawings, wherein—

Figure 1 is a sectional view of eaves and a trough suspended therefrom by the improved hanger. Fig. 2 is a view of the hanger, showing the strands of the cross-bar partially separated to more clearly illustrate their relation. Fig. 3 is a cross-sectional view through the hanger. Fig. 4 is a detail view showing a slightly-different form of trough held in place. Similar numerals of reference designate corresponding parts in all the figures of the drawings.

The hanger, as shown, comprises a trough-stirrup 10, the ends of which are secured to a strut member or cross-bar 11, which member is connected at an intermediate point with a hanger-stem 12. These several elements are formed from a single piece of wire and are constructed as follows: The cross-bar is formed of three strands or plies 13, 14, and 15, having terminal loops 16 and 17, one of said loops, 16, being downturned to form a stop that engages the inner face of the trough, the other loop, 17, projecting longitudinally from the other end of the cross-bar to form an eye in which is detachably engaged the free terminal 18 of the trough-engaging stirrup 10. One of the terminals of the wire is located at the end of the cross-bar which is provided with the eye 17, and said terminal is bent down through said eye to form a stop 19, that engages the inner face of the trough opposite to the stop 16.

The manner of constructing the hanger will be readily understood by referring to Fig. 2 and may probably be best explained as follows: Beginning at the downturned terminal or stop 19 of the wire, it will be seen that said wire is first coiled to the center of the cross-bar. Then an upstanding loop is provided, which is twisted to form the stem 12. From this stem the wire continues across to the opposite end of the cross-bar, where it is doubled upon itself, thereby forming the loop or stop 16. From this point it extends back again to the opposite end, where it is again doubled to form the outstanding loop or eye 17. From this point it is coiled about the other two strands of the cross-bar to the opposite end of the stem, where an offset portion 20 is formed that engages about the bead of the trough. The remainder of the wire constitutes the trough-stirrup 10, and the terminal 18 is detachably engaged in the eye 17, as already described. This stirrup is made long enough so that in case a trough or gutter is employed having beads at both edges the terminal 18 may be bent to surround the inner bead and still engage in the eye 17, as clearly shown in Fig. 4. The advantages of this construction may be summed up as follows: In the first place an article of manufacture is provided which is made from a single wire, and the cross-bar upon which the lateral strain is brought has three strands or plies, thus making it very strong and rigid. The downturned stops prevent the trough being jammed or flattened out, thereby making unnecessary the soldering of cross-braces into the trough. The articles are constructed in various sizes, and the hanger-stems may be made of different lengths.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. As an article of manufacture, an eaves-trough hanger, comprising a single piece of wire formed into a cross-bar having a plurality of strands, said cross-bar being provided at its ends with integral loops, one of which is downturned to constitute a stop, the other loop projecting longitudinally from the other end of the cross-bar to form an eye, one of the terminals of the wire being downturned through the longitudinally-projecting eye and constituting a depending stop, a hanger-stem projecting from the cross-bar, and a trough-engaging stirrup extending from the end of the cross-bar having the downturned loop, said stirrup having its free end detachably engaged in the eye of the cross-bar.

2. As an article of manufacture, an eaves-trough hanger comprising a single piece of wire formed into a three-strand cross-bar, said

cross-bar being provided at its ends with integral loops, one of which is downturned to constitute a stop, the other loop projecting longitudinally from the other end of the cross-bar to form an eye, said end being also provided with a depending stop, an integral hanger-stem projecting from the cross-bar, and a trough-engaging stirrup extending from the end of the cross-bar having the downturned loop, said stirrup having its free terminal detachably engaged in the eye of the cross-bar.

In testimony that I claim the foregoing as my own I have hereto affixed my signature in the presence of two witnesses.

ERNEST E. BROTT.
